UNITED STATES PATENT OFFICE.

RUDOLF GEFÄLL, OF VIENNA, AUSTRIA-HUNGARY, ASSIGNOR, BY MESNE ASSIGNMENTS, TO HARRY J. REED, OF CHICAGO, ILLINOIS.

GAS-BURNER.

No. 874,063.

Specification of Letters Patent.

Patented Dec. 17, 1907.

Application filed July 1, 1907. Serial No. 381,803.

To all whom it may concern:

Be it known that I, RUDOLF GEFÄLL, a subject of the Emperor of Austria-Hungary, and a resident of the city of Vienna, in 5 Austria-Hungary, have invented certain new and useful Improvements in Gas-Burners, of which the following is a specification in such full and clear terms as will enable those skilled in the art to construct and use the

10 same.

This invention relates to burners used for illumination, a mantle being used to produce the light, and the object of the invention is to produce a burner that will concentrate 15 the heat of the flame at the outer portion of the burner and just inside the ring formed by the mantle. The object being to produce a flame of such shape as will give the maximum light with the least gas, and to produce 20 a burner that will give a flame that will be cool at the center.

In the drawings, in which like letters of reference refer to like parts throughout, Figure 1 is a sectional view of the burner, Fig. 2 25 is a sectional view of a modified form of the burner, Fig. 1^a is a plan of the burner on the line A—B Fig. 1, and Fig. 2^a is a plan of the burner on the line C—D. Fig. 2.

The burner is of the common Bunsen type 30 and intended to be attached to any gas fixture in a well known manner, the base screwing on the fixture. Air holes are provided in the base to allow the air to mix with the gas just prior to the burning of the same. If the 35 gas is at once allowed to pass up to the mantle it is in such a small stream as to preclude the possibility of its heating the mantle near the bottom of the same, so it becomes necessary to introduce means into the top of the 40 burner to spread the gas in order that the flame may be large enough in area to completely heat the mantle. The top of the burner is spread out as shown at G, into a cylinder larger than the base of the burner, 45 and inside this top G is placed the smaller funnel shaped member H, the wider end of the funnel being placed at the top of the burner. In this funnel are placed the plates J, K which extend radially from the center 50 of the burner, as shown in Fig. 1^a, and carried by the tops of these plates is a block M placed in the center of the burner. This block and the radial plates are intended to cause the gas to spread out from the center of 55 the burner and heat the mantle better than

would be the case where the common screen is used, since the direction of flow of the gas when it escapes from the burner is somewhat transverse of the mantle fabric, L, which hangs over the burner. The same effect 60 may be produced by means of the funnels Q and R in the burner P, Fig. 2, said funnels being held in place by means of the plate T at the top of the burner.

In order to spread the gas just at the top 65 of the burner as it escapes therefrom, the block S is suspended from the plate T, and on this plate may be placed one of the blocks M, if desired.

Modifications of the invention may be 70 made within the scope of the appended claims and the right to such as come within the scope of the same is reserved.

Having thus described my invention in such full and clear terms as will enable those 75 skilled in the art to construct and use the same, what I claim as new and desire to secure by Letters Patent of the United States is as follows:

1. In a gas burner, the combination of a 80 burner of the Bunsen type having a cylindrical escape pipe, a funnel placed within said escape pipe with its small end down, means within the funnel to spread the gas to the outside of the escape pipe, and means 85 above the funnel to assist in the spreading of the gas as it escapes from the burner.

2. In a gas burner, the combination of a 90 burner of the Bunsen type having a cylindrical escape pipe, a funnel open at both ends placed within said escape pipe and having its small end down, and a series of means within said funnel and adapted to cause the stream of gas to escape from the burner as an annulus. 95

3. In a gas burner, the combination of a 100 burner of the Bunsen type having a cylindrical escape pipe, a funnel open at both ends placed within said escape pipe, and a series of radial plates placed within said funnel and adapted to cause the gas to escape from the burner as an annulus.

In testimony whereof I have hereunto set my hand in the presence of the two subscribing witnesses this 18th day of June A. D. 105 1907.

RUDOLF GEFÄLL.
